(57) **ABSTRACT**

A system of polishing a concave surface of an external piece for a timepiece, including a securing device including a support that carries the piece, and a grinding device including an abrasive mechanism rotatably mounted along a first axis and configured to polish the piece along a first curvature. The securing device further includes a moving mechanism of the support so that the support imparts a back-and-forth motion along a second axis and a contact surface of the abrasive mechanism is curved to polish the piece along a second curvature in addition to the first curvature. The system can be applied to the field of crystals for a timepiece.

SYSTEM OF POLISHING EXTERNAL
PIECES FOR A TIMEPIECECROSS-REFERENCE TO RELATED
APPLICATIONS

This is a National Phase Application in the United States of International patent application PCT/EP2012/052743 filed on Feb. 17, 2012 which claims priority on European patent application No. 11158458.7 filed Mar. 16, 2011. The entire disclosures of the above patent applications are hereby incorporated by reference.

FIELD OF THE INVENTION

The invention relates to a system of polishing an external piece for a timepiece and in particular the concave surface of a piece of this type.

BACKGROUND OF THE INVENTION

It is known to form sapphire watch crystals which are highly scratch resistant. These crystals are generally manufactured by placing a rotating grinding wheel in contact against the surface of a drum carrying several crystals. The resulting grinding operation enables a cylindrical or spherical crystal to be formed. However, it becomes necessary to form asymmetrical crystals to be fitted, for example, to timepiece displays which are not centred with respect to the timepiece case, which is not possible using current series manufacturing techniques.

SUMMARY OF THE INVENTION

It is an object of the present invention to overcome all of part of the aforesaid drawbacks by proposing a piece-by-piece polishing system which does not damage the blanks and allows improved polishing of complex concave surfaces with a very low reject rate.

The invention therefore relates to a system of polishing a concave surface of an external piece for a timepiece comprising a securing device including a support which carries said piece, a grinding device including abrasive means rotatably mounted on a first axis and intended to polish said piece along a first curvature, characterized in that the securing device further includes moving means of the support so that the support imparts a back-and-forth motion along a second axis and in that the contact surface of the abrasive means is curved to polish said piece along a second curvature in addition to the first curvature.

It is thus clear that the polishing is carried out piece-by-piece via the contact of the piece against the abrasive means. The back-and-forth motion of the support thus forces the piece to follow the curved contact surface of the abrasive means. Polishing is thus performed by the movement of the pieces one-by-one against the abrasive means, rotatably mounted along a fixed axis, which provides a very low reject rate by avoiding damage to the rough concave surface before polishing.

In accordance with other advantageous features of the invention:

the moving means is formed by a rotating actuator driving a crank-shaft which is connected off-centre to a connecting rod integral with said second axis to form said back-and-forth motion;

2

the moving means is mounted on a set of selectively movable carriages so as to compel the piece to be polished to exert a force against said abrasive means; said first axis and said second axis are substantially perpendicular;

the abrasive means is formed by a grinding wheel; the piece is formed from crystallised alumina.

BRIEF DESCRIPTION OF THE DRAWINGS

Other features and advantages will appear clearly from the following description, given by way of non-limiting illustration, with reference to the annexed drawings, in which:

FIG. 1 is a view of a system of machining blanks according to the invention;

FIG. 2 is a schematic view of a polishing system according to the invention;

FIGS. 3 and 4 are views of a blank at two different manufacturing stages;

FIG. 5 is a schematic view of the moving means of the securing device according to the invention;

FIGS. 6 to 8 are top views of the moving means of the securing device at various phases of motion.

DETAILED DESCRIPTION OF PREFERRED
EMBODIMENTS

The invention relates to an external piece for a timepiece such as a crystal, case or dial made of crystallised alumina-based material, such as sapphire, corundum or ruby. The invention relates to new manufacturing systems for producing blanks and then polishing pieces of complex shape.

Naturally, although the invention was developed for the field of horology, it is not limited thereto. Other applications may also be envisaged such as optics, tableware or electronics.

As illustrated in FIG. 1, a manufacturing system 1 has been developed in order to produce external pieces 3 comprising surfaces whose curvatures C_1 , C_2 are concave. Manufacturing system 1 includes a securing device 5 and a machining device 7.

Securing device 5 includes a drum 11, rotatably mounted along a first axis A_1 , and carrying at least one blank 3' of the future piece 3. Preferably, as seen in FIG. 1, drum 11 is a ring comprising a faceted inner wall, i.e. provided with successive planes P . As illustrated in FIG. 1, each successive plane P_x receives a blank 3' which may be secured, for example, by bonding.

Machining device 7 includes an abrasive means 13 which is rotatably mounted along a second axis A_2 and which is intended to machine each blank 3'. Preferably, abrasive means 13 is moved in the hollow of ring-shaped drum 11. The abrasive means 13 shown in FIG. 1 is formed by a conventional grinding wheel, i.e. whose contact area does not have any particular shape. Of course, abrasive means 13 may be different and, for example, take the form of a curved or conical sabot.

Advantageously according to the invention, the machining device 7 includes moving means 15 of the second axis A_2 so that said device is movably mounted along a curved directrix to selectively form a second curvature C_2 in each blank 3'. It is thus clear that manufacturing system 1 can form first and second concave curvatures C_1 , C_2 .

According to the invention, moving means 15 may, in a non-limiting manner, be formed by an actuator moved back-and-forth against the profile of a fixed cam correspond-

ing to the second curvature C_2 or, for example, an automated device programmed to move along said second curvature.

Thus, the first curvature C_1 is generated perpendicular to axis A_1 by the radius extending between axis A_1 and the contact area between abrasive means 13 and each blank $3'$. Since drum 11 is moved in rotation along axis A_1 , each blank $3'$ is thus hollowed out transversely along a single radius forming the first concave curvature C_1 .

Moreover, the second curvature C_2 is directly obtained by selectively moving the second axis A_2 . Thus while the first curvature C_1 is being generated, the contact area between abrasive means 13 and each blank $3'$ is gradually moved relative to the thickness of ring-shaped drum 11 . Consequently, each blank $3'$ is hollowed out longitudinally along a curved directrix forming the second concave curvature C_2 .

It is therefore immediately clear that the curved directrix of moving means 15 may or may not be symmetrical in order to form the second curvature C_2 on one or several radii. By way of example, it is possible to start with a blank $3'$ comprising a top face 12 and a bottom face 14 shown in FIG. 3. After modification by manufacturing system 1 , the resulting blank $3'$ may then include one of these faces $12, 14$ with a transverse concave surface comprising a curvature C_1 and a longitudinal concave surface comprising a curvature C_2 .

Finally, preferably according to the invention, the first axis A_1 and the second axis A_2 are perpendicular so that the machining lines intersect. This feature advantageously facilitates the subsequent polishing of external pieces 3 .

Polishing a concave surface like that formed from curvatures C_1 and C_2 was attempted with tools similar to the system of manufacturing system 1 , i.e. mainly by replacing the type of abrasive means. However, this attempt did not provide satisfaction, since this type of polishing caused a deformation of curvatures C_1, C_2 , particularly on the edges of the blanks $3'$ to be polished and consequently resulted in too high a reject rate.

Consequently, a manufacturing system 21 was developed for pieces of the type $3'$ illustrated in FIG. 4, namely comprising surfaces whose curvatures C_1, C_2 are concave. As illustrated in FIG. 2, the manufacturing system 21 includes a securing device 25 and a grinding device 27 .

Grinding device 27 includes an abrasive means 33 rotatably mounted along an axis A_3 and designed to polish each piece $3'$ along a first curvature C_1 . Preferably according to the invention, the contact surface of abrasive means 33 includes a curved surface for polishing piece $3'$ along a second curvature C_2 in addition to said first curvature C_1 . The abrasive means 33 shown in FIG. 2 is preferably formed by a disc whose grinding surface includes a convex surface, for example made of metal, which is regularly coated with a polishing liquid.

Securing device 25 includes a support 31 which carries the piece $3'$ to be polished. Preferably according to the invention, the securing device 25 further includes moving means 35 of the support 31 to impart a back-and-forth motion along an axis A_4 . It should be noted in FIG. 2 that axis A_4 is substantially perpendicular relative to the axis A_3 of rotation of abrasive means 33 .

Thus, moving means 35 enables the blank $3'$ of piece 3 to be both pressed and to move in order to force the friction of abrasive means 33 against each blank $3'$ in order to polish said pieces selectively along second curvature C_2 . It is thus clear that polishing system 21 can polish first and second concave curvatures C_1, C_2 .

According to the invention, moving means 35 enables blank $3'$ of piece 3 to be pressed and moved relative to

abrasive means 33 . The moving means 35 will be better understood with reference to FIGS. 5 to 8.

Preferably according to the invention, the moving means 35 is formed by a rotating actuator 32 driving a substantially discoid crank-shaft 34 which is connected off-centre to a connecting rod 36 integral with axis A_4 in order to form the desired back-and-forth motion B .

The connecting rod 36 in the example illustrated in FIGS. 5 to 8 includes two arbours 37 and 38 . Arbour 37 thus connects the stud 39 of crank-shaft 34 , which is off-centre with respect to the axis of actuator 32 , to arbour 38 . Arbour 38 , pivotably mounted along axis A_4 , connects arbour 37 and support 31 . An illustration of motion B is shown in FIGS. 6 to 8.

FIG. 6 shows the moving means 35 in one of the extreme positions of motion B . In this first extreme position, the two arbours $37, 38$ of connecting rod 36 form an acute angle with respect to each other. It is thus clear that when crank-shaft 34 imparts a backward rotation, as illustrated in FIG. 6, this causes a trigonometric rotation of arm 38 and, incidentally, of support 31 with respect to axis A_4 .

FIG. 7 shows moving means 35 in a substantially central position of motion B . In this position, the two arbours $37, 38$ of connecting rod 36 form a substantially right angle with respect to each other. It is thus clear that if crank-shaft 34 continues its backward rotation illustrated in FIG. 7, this again causes a trigonometric rotation of arm 38 and, incidentally, of support 31 with respect to axis A_4 .

FIG. 8 shows moving means 35 in the second extreme position of motion B . In this second extreme position, the two arbours $37, 38$ of connecting rod 36 form an obtuse angle with respect to each other. It is thus clear that when crank-shaft 34 imparts a backward rotation, as illustrated in FIG. 8, this causes a backward rotation of arm 38 and, incidentally, of support 31 with respect to axis A_4 until the return to the first extreme position passing through the same substantially central position.

Consequently, the rotating motion of actuator 32 is converted by the crank-shaft 34 -connecting rod 36 assembly into a back-and-forth motion of support 31 .

Preferably according to the invention, the moving means 35 is also mounted on a set 41 of carriages that are moveable selectively longitudinally C , transversely D , and vertically E . This not only enables support 31 to be precisely positioned with respect to abrasive means 33 , but also provides the desired pressing action. Indeed, in order to force the piece to be polished via support 31 to exert a force against abrasive means 33 , the longitudinal carriage is controlled in a motion C greater than the space between blank $3'$ of piece 3 to be polished and abrasive means 33 .

It is thus clear that polishing is performed piece-by-piece by pressing blank $3'$ against abrasive means 33 , the back-and-forth motion of support 31 forcing blank $3'$ to follow the curved contact surface of abrasive means 33 . Polishing is thus performed by moving a blank $3'$ piece-by-piece against abrasive means 33 rotatably mounted along a fixed axis A_3 which provides a very low reject rate.

The piece 3 obtained after modification of blank $3'$ by polishing system 21 thus includes one of these faces $12, 14$ with a transverse concave surface comprising a curvature C_1 and a longitudinal concave surface comprising a curvature C_2 which are perfectly polished. Pieces 3 may also be subjected to a final chemical super-polishing step to further improve their appearance.

Of course, this invention is not limited to the illustrated example but is capable of various variants and alterations that will appear to those skilled in the art. In particular,

5

abrasive means 33 may be different and, for example, take the form of a curved or conical sabot.

It is also understood that the moving means 35 may be of a different nature to obtain the same type of pressing action and back-and-forth motions B.

The invention claimed is:

1. A system of polishing a concave surface of an external piece for a timepiece, comprising:

a securing device including a support that carries only the external piece; and

a grinding device including an abrasive mechanism formed by a disc rotatably mounted along a first axis to polish the external piece along a first curvature, the disc being substantially cylindrically shaped and including a first face and a second face with a peripheral wall therebetween, an orientation of the disc defined by a plane perpendicular to the first axis and equally dividing the disc;

wherein the securing device further includes a moving mechanism of the support so that the support imparts a repeated, oscillating motion around a second axis that is located within the plane, the external piece remaining in contact with the disc during the repeated, oscillating motion;

wherein a contact surface of the abrasive mechanism formed on the peripheral wall of the disc is curved to polish the piece along a second curvature in addition to the first curvature, and

wherein the peripheral wall includes the first curvature and the second curvature.

2. The system according to claim 1, wherein the moving mechanism includes a rotating actuator driving a crank-shaft connected of to a connecting rod integral with the second axis to form a back-and-forth motion.

3. The system according to claim 1, wherein the moving mechanism is mounted on a set of selectively moveable carriages to force the piece to be polished to exert a force against the abrasive mechanism.

4. The system according to claim 1, wherein the first axis and the second axis are substantially perpendicular.

5. The system according to claim 1, wherein the abrasive mechanism includes a grinding wheel.

6

6. The system according to claim 1, wherein the first curvature is a single concave radius.

7. The system according to claim 1, wherein the second curvature is a symmetrical concave curvature.

8. The system according to claim 1, wherein the second curvature is a non-symmetrical concave curvature.

9. The system according to claim 8, wherein the second curvature is formed by plural concave radii.

10. The system according to claim 1, wherein the first curvature is different from the second curvature.

11. The system according to claim 1, wherein the support undergoes an automated back-and-forth motion around the second axis.

12. The system according to claim 1, wherein a radius of the first curvature is measured around the first axis and a radius of the second curvature is measured around the second axis.

13. A system of polishing a concave surface of an external piece for a timepiece, comprising:

a securing device including a support that carries only the external piece; and

a grinding device including an abrasive mechanism formed by a disc rotatably mounted along a first axis to polish the external piece along a first curvature, the disc being substantially cylindrically shaped and including a first face and a second face with a peripheral wall therebetween, an orientation of the disc defined by a plane perpendicular to the first axis and equally dividing the disc;

wherein the securing device further includes a moving mechanism of the support so that the support imparts a repeated, oscillating motion around a second axis that is located within the plane, the external piece being ground during the repeated, oscillating motion.

14. The system according to claim 1, wherein the repeated, oscillating motion around the second axis moves the peripheral wall across the support from one extreme position to another extreme position.

15. The system according to claim 13, wherein the repeated, oscillating motion around the second axis moves the peripheral wall across the support from one extreme position to another extreme position.
